UNITED STATES PATENT OFFICE.

LYNN G. LINDSAY, OF MINNEAPOLIS, MINNESOTA.

CONTROL MECHANISM FOR WATER SOFTENERS.

Application filed July 6, 1925. Serial No. 41,657.

This invention relates to new and useful improvements in control mechanisms particularly designed for use in conjunction with water softeners such as are used in homes and other buildings to soften the hard water delivered thereto from the usual water mains of public or private water systems, and more particularly relates to such a mechanism adapted for remote control to automatically control the flow of water and brine solution through the apparatus during the process of reconditioning or revivifying the mineral bed in the pressure tank thereof.

15 An object of the invention is to provide a control mechanism which may be constructed and assembled as a unit, and is adapted for use in connection with ordinary water softeners employing a plurality of manually operable control valves, whereby such an apparatus may readily and conveniently be converted into an automatically operable device adapted for remote control, in a minimum amount of time.

25 The particular object therefore of the invention is to provide an improved control mechanism for water softeners, and which mechanism is an improvement over the form shown in my prior co-pending application, Serial No. 35,374, filed June 6, 1925.

Other objects of the invention will appear from the following description and will be pointed out in the annexed claims.

In the drawings there has been disclosed a structure designed to carry out the various objects of the invention but it is to be understood that the invention is not confined to the exact features shown as various changes may be made within the scope of the claims which follow.

In the drawings,

Figure 1 is a view in perspective showing the improved control mechanism mounted upon a water softener of the form commonly known as an upward flow and upward reconditioning type;

Figure 2 is an enlarged detail sectional view of one of the fittings of the control mechanism;

50 Figure 3 is an enlarged detail sectional view showing a form of an injector valve used in drawing the brine solution from the brine tank and discharging it into the pressure tank;

55 Figure 4 is an enlarged detail sectional view showing the restricted passage prefer-

ably provided through the discharge end of the hard water supply pipe to the brine tank;

Figure 5 is a plan of one form of motor 60 for operating the valves;

Figure 6 is a detail vertical section showing the normal position of the control mechanism of the motor;

Figure 7 is a view similar to Figure 6 65 showing the mechanism in process of closing or opening the valves.

In the selected embodiment of the invention here shown there is illustrated a water softener comprising the usual pressure tank 70 mounted upon suitable legs 8 and having a mineral bed 9 therein, as is customary in structures of this type. A hard water intake pipe 11 is connected with the lower portion of the tank and has a distributor 12 75 connected thereto which is positioned within the tank and through which the hard water is delivered to the tank. A union or coupling 13 is provided on the intake pipe 11 to provide means for connecting it to the 80 control mechanism which will subsequently be described. The usual soft water outlet pipe 14 is shown connected to the upper portion of the pressure tank 7. This pipe leads to and is connected with the water distributing pipe within the building. A check valve 15 is interposed in the pipe 14 to prevent the water in the houseline from returning to the tank when the water pressure therein is released by draining the water 90 therefrom during the process of re-conditioning the mineral bed. A pipe section 16 leads from the soft water outlet pipe 14 and is provided with a union or coupling 17 to provide means for connecting it to the 95 control mechanism.

A feature of this invention resides in the novel construction and arrangement of the control mechanism adapted to automatically control the flow of water and brine solution 100 through the apparatus during the process of re-conditioning the mineral bed 9 in the pressure tank. This control mechanism is so constructed that it may be assembled as a unit and connected to a water softener of 105 ordinary construction, and of the manually operated type, thereby converting such a water softener into an automatically controlled device.

A pipe section 18 is adapted to have one 110 end connected to the union 13 of the hard water intake pipe 11 while its other end is

in connection with the hard water supply pipe 19 through a pipe-fitting 21, as shown in Figures 1 and 2. A pipe section 22, having one end connected to the union 17 of the pipe connection 16, is also preferably connected to the pipe-fitting 21 by means of a plug 23 and T-fitting 24 as shown particularly in Figure 2. A nipple 25 is mounted in the T-fitting 24 and has a valve 26, of ordinary construction, and preferably of the type commonly known as a whistle valve, connected thereto, the other end of which is connected to a drain pipe 27 as shown. When the valve 26 is opened, communication is established between the drain pipe 27 and the interior of the upper portion of the tank 7 so that the water contained therein under pressure may be drained therefrom.

20 A similar valve 28 is also interposed in the hard water supply pipe 19 adjacent the pipe fitting 21. This valve controls the flow of raw water under pressure, and also the flow of brine into the pressure tank during the period in which the mineral bed is being re-conditioned. The operating levers 29 of the valves 26 and 28 are operatively connected, by means of rods 31, to the crank arms 32 of a control motor or device 33, preferably of the electrically operated type such as are commonly used in connection with heating apparatuses to automatically control the operation thereof. The control motor or device 33 is preferably mounted upon a supporting rod or standard 34 having its lower end suitably secured to the pipe fitting 21. Other electrically operated devices such, for instance, as a solenoid or relay, may also be employed to automatically operate the control valves by remote control, instead of the particular type shown in the drawings; or, if desired a spring or weight actuated device or a water-motor may be employed without departing from the invention.

50 The means provided for drawing a predetermined quantity of brine from the brine tank 35 and delivering it into the pressure tank 7 preferably consists in the provision of an injector valve 36, of ordinary construction, and which is sometimes called an injector valve. (See Figure 3.) This injector valve is provided with the usual nozzle 37 connected to the hard water supply pipe 19 by means of the pipe sections 38 and 39 and the T-fitting 41 as shown in Figure 1. The opposite end of the injector valve 36 is connected with the pipe fitting 21 by means of the pipe section 42, thereby establishing communication between the injector valve and the pipe fitting 21, and therefore the hard water intake pipe 11, through the pipe section 18. A ball valve 43, of ordinary construction, and having the usual float 44 adapted to float in the brine tank,

55 is interposed between the T-fitting 41 and a similar fitting 45 having a pipe section 46 connected thereto through which hard water is delivered to the brine tank from the hard water supply pipe 19 during and following the re-conditioning operation of the apparatus. A cap 47, having a restricted passage 48 therein, is preferably mounted in the discharge end of the pipe section 46 to restrict the flow of water therefrom into the brine tank. (See Figure 4.) It will also be noted by reference to Figure 1 that the discharge end of the pipe 46 extends downwardly into the brine tank a distance sufficient to insure that the minimum level in the 80 brine tank will always be above the discharge end of the pipe, thereby preventing air from being drawn into the pipe during the re-conditioning period while the injector is in operation, which would ultimately be 85 discharged into the pressure tank, thereby causing bubbles to rise therein with a resultant agitating of the mineral bed, and therefore a loss of mineral as a result of a portion thereof being discharged through 90 the waste water pipe 6 and into the sewer.

95 A suction pipe 49 is mounted in the brine tank 35 and has its lower end preferably secured to a convex plate or disc 51 which is spaced from the bottom of the brine tank and functions to draw brine evenly through the entire salt bed as well as to prevent particles of salt from being drawn into the pipe 49 when brine is being delivered to the pressure tank. The upper end of the suction 100 pipe 49 is connected to one side of a check valve 52, of ordinary construction, having its other end in communication with the injector valve 36 by means of nipples 53 and 54, and the T-fitting 55. A similar check 105 valve 57 is mounted between the hard water pipe 46, leading from the supply pipe 19 to the brine tank, and the T-fitting 55 which is in communication with the suction pipe 49, thereby establishing one-way circulation 110 between the hard water pipe 46 and the T-fitting 55 during the operation of re-conditioning the mineral bed in the pressure tank. Unions or couplings 58 are preferably provided between the nipple 38 and the injector 115 valve 36 and also between the nipple 54 and the valve, whereby the injector valve may readily and conveniently be removed from the control mechanism for such purposes as cleaning or repairing.

120 In the operation of this novel control mechanism in conjunction with a water softener, such as shown in the accompanying drawings, and when the valve 28 is open and the valve 26 is closed, as when 125 functioning under normal operating conditions, hard water will flow from the pipe 19 through the open valve 28, pipe fitting 21, pipe sections 18 and 11; through the distributor 12 and into the lower portion of 130

the brine tank, after which it will upwardly flow through the mineral bed 9 which will absorb the hardness of the water so that the resultant flow from the upper portion of the 5 tank through the pipe 14 and check valve 15 will be soft water. During the normal operation of the water softener, the circulation of water through the apparatus will be as above described.

10 After a predetermined amount of hard water has been passed through the mineral bed and softened, the mineral bed, as a result, loses its water softening characteristics after which it becomes necessary to re-condition 15 the mineral bed before it again will be effective to soften the hard water passed therethrough. The process of re-conditioning the mineral bed to render it effective again as a water softener consists of passing 20 a solution of salt water or brine therethrough, and thereafter rinse or cleanse the mineral substance with fresh water, after which the mineral again becomes active as a water softener.

25 The purpose of the novel control mechanism featured in this invention is to provide means for automatically controlling the flow of water and brine through the pressure tank during the operation of re-conditioning the 30 mineral bed, which operation is performed periodically depending upon the amount of water drawn from the apparatus.

In the operation of re-conditioning the mineral bed, as above mentioned, the control 35 valve 28 is closed by the operation of the control motor 33 which operation will simultaneously open a similar valve 26 so that the water remaining in the pressure tank will be discharged therefrom through the 40 waste water pipe 27 and into a sewer or other receiving means. As soon as the control valves 26 and 28 have been actuated by the motor, as above described, the hard water from the supply pipe 19 will be caused to 45 flow through the pipe section 39, T-fitting 31, nipple 38 and through the injector valve 36; thence through the pipe section 42 and back to the pipe fitting 21, after which it will downwardly flow through the pipe sections 50 18 and 11 and into the lower portion of the pressure tank. Such circulation of the water around the control valve 28 and through the injector valve 36 will cause a vacuum to be built up or generated in the intake 59 of the 55 injector valve, which intake is connected with the suction pipe 49, through the nipples 53 and 54, T-fitting 55, and the check valve 52, thereby causing a portion of the brine to be upwardly drawn into the suction 60 pipe 49 and into the injector valve 36. The brine thus delivered to the injector valve will be carried by the water flowing therethrough into the lower portion of the pressure tank and will upwardly circulate therethrough and into the pipe sections 16 and 65 22 and through the open control valve 26; thence through the waste water pipe 27 and into the sewer. As soon as the brine begins to flow from the brine tank into the pressure tank, as above described, the brine level in the tank 35 will begin to lower, thereby causing the float valve 43 to open as the float 44 lowers, caused by the flowing of the brine from the brine tank. Such discharging of the brine from the brine tank, however, will be interrupted after a predetermined quantity has been discharged therefrom and the ball valve 43 is opened sufficiently to cause the flow of hard water from the T-fitting 43 through the check valve 57 and into the fitting 55, to cause a pressure to be built up in the nipples 53 and 54 which will cause the check valve 52 to automatically close and thereby interrupt the flow of brine from the brine tank. The above condition is caused as a result of the restricted passage 48 in the discharge end of the pipe section 46, which is not of sufficient size to cause the full volume of water to be discharged therefrom when the valve 43 is open, thereby causing the aforementioned pressure to be built up in the nipples 53 and 54 and the pipe fitting 55, and thus causing the check valve 52 to close. Hard water will thereafter continue to flow through the injector valve 36 and also through the open ball valve 43 and into the pipe sections 42, 18 and 11 and into the bottom of the pressure tank until the mineral bed has been sufficiently cleansed after which the control motor 33 will be actuated to cause the valve 28 to be opened and the discharge valve 27 to be closed after which the complete cycle of re-conditioning the mineral bed has been completed, and the apparatus is again ready for normal functions. Obviously, fresh water will continue to flow into the brine tank 35 until the maximum level of water or brine therein is attained after which the ball valve 33 will be closed and the flow of water therethrough interrupted. In the operation of the mechanism, it is to be understood that when the check valves 52 and 57 are so arranged that under normal operating conditions the pressure of the portion of water flowing through the injector valve will be sufficient to cause both check valves to remain closed, thereby preventing the hard water from entering the brine tank when the ball valve 43 is in closed position. It will also be seen that during the process of re-conditioning the mineral bed, that as the ball valve 43 is opened by the lowering of the brine level in the brine tank, water will commence to flow through the check valve 57 which, after a predetermined opening of the valve 43, will cause sufficient pressure to be built up against the discharge side of the check valve 52 resulting in its being automatically closed to interrupt the flow of brine from the brine tank.

From the foregoing, therefore, it will be noted that the operation of delivering the brine to the brine tank, and also of supplying fresh water to the brine tank is automatically controlled by the actuation of the two control valves 26 and 28 by the control motor 33; also by the use of the two check valves 52 and 57 and the ball valve 43 to control the flow of brine from the brine tank and the introduction of fresh water thereto, a positive control is provided, thereby preventing any air from being drawn into the pressure tank and also insuring the efficient operation of the apparatus as a whole.

15 The control mechanism may also readily and conveniently be detached from the pressure tank by simply uncoupling the pipe section 22 from the soft water pipe connection 16, and also the pipe section 18 from the 20 hard water intake pipe 11 by means of the two unions or couplings 13 and 17.

Any preferred form of motor may be used for simultaneously operating the hard, and waste water control valves, the construction 25 of a commercial form of motor, which can be utilized for the present purpose, being illustrated in Figures 5, 6 and 7. No claim is made for the construction of this motor which is only illustrative of one form of the 30 device adapted for use, as an element of the combination, for simultaneously operating the valves for the purpose described.

The device comprises a driven shaft 100 having the cranks 32 at opposite ends, arranged at an angle of 180°, and in this instance vertical. The shaft is driven by a suitable power, in this instance a spring motor 101, said motor having gearing connecting it with the shaft 100. Means is provided for causing rotation of the shaft through successive arcs of 180°, and latch mechanism is provided for starting and stopping shaft rotation, this effect being automatically produced by the following mechanism:

A pair of coils 103 are suitably controlled by a circuit shown in diagram, in turn controlled by a suitable switch such as a push button. Upon the shaft 100 is secured a 50 disc 104 having notches 105, as stops diametrically related. A lever 106 is suitably pivoted as at 107 and has an arm 108, as an armature for the coils, and further has an arm 109, the end of which is adapted to engage the disc stops as a pawl. Upon energizing the coils, the pawl is released, the shaft rotates, and the arm 109 rides against the periphery of the disc until it engages the succeeding notch, the weight 110 acting to 55 maintain the engagement of the arm against the periphery of the disc. A governor shaft 112 carrying the wings 113, has an arm 115 engageable with the stop 115' of the armature, whereby, when the armature rises, as a 60 result of the engagement of the pawl with

the notch, the arm 114 engages the stop to prevent further rotation of the shaft 100, this being accomplished through a gear train suitably connecting the shaft 100 with the governor shaft. Thus, upon momentarily closing the switch 118, the pawl releases, the disc rotates through an arc of 180°, then stops, and the valves can thus be made to close and open intermittently and alternately. 75

I claim as my invention:

1. A device of the class described comprising a bed tank having a hard water supply pipe, a valve for said pipe, a brine tank, pipe connections between the hard water pipe and brine tank, including an injector arranged for sucking brine from the brine tank when the hard water valve is closed, an auxiliary hard water pipe within the brine, a valve in the auxiliary line controllable by brine level, and pipe connections between brine and auxiliary hard water pipes, including automatically operable valves adapted to open toward the injector. 80

2. A device of the class described comprising a bed tank having a hard water supply pipe, a valve for said hard water pipe, a by-pass connecting the hard water pipe around the hard water valve and including an injector delivering in the direction of the tank, a brine tank, a brine pipe connecting with the suction side of the injector and said brine pipe having a check valve, an auxiliary hard water delivery pipe connecting the hard water supply with the brine tank, a valve in the auxiliary pipe adapted to be opened as the brine level is lowered, and a cross connection between said brine pipe and auxiliary pipe connecting at one end between the injector and check valve of the brine pipe, and at the opposite end between the valve and brine tank, and having a check valve therein. 95

3. A device of the class described comprising a bed tank having hard water supply pipe, a soft water delivery pipe, and a waste water discharge pipe, said hard water and waste water pipe each having a valve, a by-pass connecting the hard water pipe around the hard water valve and including an injector delivering in direction of the tank, a brine tank, a brine pipe connecting with the suction side of the injector, said brine pipe having a check valve, an auxiliary hard water delivery pipe connecting the hard water supply with the brine tank and having a reduced diameter within the brine, a valve in the auxiliary pipe adapted to be opened as the brine level is lowered, and a cross-connection between said brine pipe and auxiliary pipe, connecting at one end between the injector and check valve of the brine pipe, and at the opposite end between the valve and brine tank, and having a check valve therein, and common means operable 100

to substantially simultaneously open the waste water valve and close the hard water valve and vice versa.

4. A device of the class described comprising a bed tank having a hard water supply pipe, said hard water supply pipe having a valve, a brine tank, and an auxiliary hard water supply pipe leading thereto, said auxiliary pipe having a valve controlled by the brine level, a hard water by-pass connection with the bed tank around said hard water control valve, said by-pass having an injector therein operating toward the bed tank, and having a suction pipe connection with the brine, a check valve in the brine suction connection, opening toward the injector, and pipe connections between the brine suction pipe and auxiliary hard water pipe, including a check valve arranged to weaken injection effects and build up back pressure between the brine pipe check valve, and the injector.

5. A device of the class described comprising a bed tank having a hard water supply pipe, said hard water pipe having a valve, a by-pass connecting the hard water pipe around the hard water valve, including an injector delivering in direction of the tank, a brine tank, a brine pipe connecting with the suction side of the injector, and having a check valve adapted to open toward the injector, an auxiliary hard water delivery pipe connecting the hard water supply with the brine tank, a float controlled valve in the auxiliary pipe adapted to be opened as the brine level is lowered, and a cross connection between said brine pipe and auxiliary pipe, connecting at one end between the injector and check valve of the brine pipe, and at the other end between the float valve and brine tank, and having a check valve therein adapted to open toward the injector.

6. A device of the class described comprising a bed tank having a hard water supply pipe, said hard water pipe having a valve, a by-pass connecting the hard water pipe around the hard water valve, including an injector delivering in direction of the tank, a brine tank, a brine pipe connecting with the suction side of the injector, and having a check valve adapted to open toward the injector, an auxiliary hard water delivery pipe connecting the hard water supply with the brine tank, a float controlled valve in the auxiliary pipe adapted to be opened as the brine level is lowered, and a cross connection between said brine pipe and auxiliary pipe, connecting at one end between the injector and check valve of the brine pipe, and at the other end between the float valve and brine tank, and having a check valve therein adapted to open toward the injector.

7. A device of the class described comprising a bed tank having a hard water supply tank, a soft water delivery pipe, and a waste water discharge pipe, said hard water supply pipe and soft water delivery pipe each having a valve, a brine tank and an auxiliary hard water supply pipe leading thereto, said pipe having a valve controlled by the brine level, a hard water by-pass connection with the bed tank around said hard water control valve, said by-pass having an injector therein operating toward the bed tank, and having a suction pipe connection with the brine, a check valve in the brine suction connection opening toward the brine tank, pipe connections between the brine suction and auxiliary hard water pipes including valves arranged to weaken injector effects and build up back pressure between the brine pipe check valve and the injector, and common means for substantially simultaneously operating the hard water and drain valves to close one and open the other, and vice versa.

In witness whereof, I have hereunto set my hand this 30th day of June, 1925.

LYNN G. LINDSAY.
